UNITED STATES PATENT OFFICE

2,517,905

BLOCK REMOVER AND CONVEYER FOR CONCRETE BLOCK MACHINES

Thomas J. Matthews, Paradise, Pa.

Application July 16, 1948, Serial No. 39,132

3 Claims. (Cl. 25—1)

1

This invention relates to concrete block making machines.

An object of this invention is to provide a timed means for automatic removal of the formed concrete blocks from a block making machine at the time the formed block on the pallet is removed from the machine by the ejector, the operation of the ejector providing the timing means for effecting operation of the device in one cycle thereof.

Another object of this invention is to provide an electrically operated block removing means which will remove the formed block from the molding machine, the device including a reciprocating carriage movable between a pair of conveyor chains and adapted to raise the block for movement over the forward ends of the chains and then to lower the block onto the chains. During each cycle of the carriage embodying the forward and return movement thereof, the conveyor chains will move a distance slightly greater than the thickness of a block, so that a number of blocks will accumulate on the conveyor chains for subsequent removal by a lifting device.

Another object of this invention is to provide a magnetic switch connected between the motor and the block ejector and adapted to be initially energized by closing of a switch actuated upon by the ejector, and to be de-energized when the carriage completes an operating cycle.

A further object of this invention is to provide a machine of this kind which is automatic in operation, being regulated by operation of the molding machine.

With the above and other objects in view, my invention consists in the arrangement, combination and details of construction disclosed in the drawings and specification, and then more particularly pointed out in the appended claims.

In the drawings,

Figure 1 is a detail side elevation of a device constructed according to an embodiment of this invention, for removing concrete blocks from a molding machine.

Figure 2 is a detail side elevation of the device.

Figure 3 is a sectional view taken on the line 3—3 of Figure 1.

Figure 4 is a sectional view taken on the line 4—4 of Figure 1.

Figure 5 is a fragmentary sectional view taken on the line 5—5 of Figure 1.

Figure 6 is a fragmentary sectional view taken on the line 6—6 of either Figure 3 or 5.

Figure 7 is a diagrammatic view showing the electric circuits embodied in this invention.

2

Figure 8 is an enlarged fragmentary side elevation of the forward end of the machine.

Figure 9 is a fragmentary transverse section showing one of the conveyor chains and the support therefor.

Referring to the drawings, the numeral 10 designates generally a frame structure which is formed of a pair of upper horizontal channel members 11 secured to upright supports 12. The supports 12 have secured to the lower portions thereof lower horizontal frame members 13 and the uprights 12 have secured therebetween transverse connecting members 14.

The frame 10 has mounted on the upper portion thereof a pair of conveyor chains 15 and 16 which are trained about rear sprockets 17 and 18 and forward sprockets 19 and 20 respectively. The rear sprockets 17 and 18 are secured to a rear shaft 21 journalled in bearings 22 and the front sprockets 19 and 20 are secured to a shaft 23 journalled in bearings 24. The shaft 21 has secured thereto a sprocket 25 about which a chain 26 is trained and the chain 26 engages a relatively small speed reducing sprocket 27 which is fixed to a crankshaft 28 journalled in bearings 29. The crankshaft 28 has fixed thereto a sprocket 30 about which a driving chain 31 is trained and the chain 31 also engages about a reduced sprocket 32 operated from a speed reducing means 33 which is connected by a motor shaft 34 to a motor or power member 35.

The upper runs of the chains 15 and 16 slidably engage rails 36 which are fixed to the channel members 11 and as herein disclosed the chains 15 and 16 are of the roller type with the rail 36 engaging between the links of the chain so that the rollers 37 will ride on the rails 36.

A reciprocal slide member generally designated as 38 is slidably disposed between the guide members 11 and includes a pair of elongated side bars 39 connected together by connecting bars 40 and rollers 41 extend from the side bars 39 and engage within the channels of the channel members or guides 11. The forward end of the slide or carriage 38 includes relatively narrow bars 42 which are adapted upon forward movement of the carriage 38 to engage beneath the pallet 43 carrying a concrete block 44. The pallet 43 is raised upwardly from a block forming mold 45 which forms a part of a conventional molding machine, and the pallet 43 is raised upwardly by means of ejector rods 46.

The carriage 38 is moved lengthwise of the frame by means of an elongated rock lever 47 pivotally mounted as at 48 in the frame 10. The upper end of the rock lever 47 is connected by

means of a link 49 to the carriage 38 and the lever 47 is connected by means of a pitman or link 50 to the crank 51 of the crankshaft 28.

As will be noted in the drawings, the upper edges of the carriage side members 39 are disposed slightly below the upper edges of the conveyor chains 15 and 16. This arrangement of the carriage with respect to the conveyor chains is provided so that a number of blocks 44 may be disposed on the chains 15 and 16 with the carriage 38 movable therebeneath and out of contact with the pallets 43 on which the blocks 44 are positioned.

In order to provide a means whereby the concrete blocks with their pallets may be discharged onto the conveyor chains, I have provided an elongated lifting member 52 which is pivotally mounted as at 53 between the side members 39 of the carriage 38. This lifting member 52 is constructed in the form of an elongated flat member which projects forwardly between the arms 42. The lifting member 52 is adapted to be raised upwardly to position the block mounted thereon above the conveyor chains by means of a cam 54 which is mounted on a cam shaft 55. A depending cam engaging roller 56 carried by a support 57 secured to the lower side of the lifting member 52 is adapted upon rearward movement of the carriage to engage a rockable plate 58 which engages the cam 54. The plate 58 is pivoted at its forward end as at 59 between the bearings or supports for the forward shaft 23 and when the high part of the cam 54 raises plate 58, roller 56 will ride on the plate 58 so that lifting member 52 will be raised a short distance above the chains 15 and 16. Cam shaft 54 is rotated by means of a chain 60 engaging about a sprocket 61 secured to shaft 55 and also engaging about a sprocket 62 secured to crankshaft 28.

In order to provide for automatic operation of the carriage and conveyor structure, I have provided a magnetic switch 63 which is connected at one side 64 thereof to a source of electric current supply. The magnetic switch 63 is normally biased to an open position and the other side of the switch 63 is connected by means of a conductor 65 to a conductor 66. The conductor 66 is connected to a stationary contact 67 of an ejector operated switch 68.

The movable arm 69 of the switch 68 is spring-pressed to an open position and is disposed in the path of a switch operator 70 which is secured to the lower ejector plate 71. The movable switch arm 69 is connected by a conductor 72 to a second supply conductor 73 which is connected to the motor 35. The opposite side of the motor 35 is connected by a conductor 74 to a cam operated switch 75 having a spring-pressed switch arm 76 normally urged to circuit closing position.

The stationary contact 77 of switch 75 is connected by a conductor 78 to the stationary contact 79 of magnetic switch 63. Switch arm 76 is disposed in the path of a circuit breaking arm 80 which is fixed to cam shaft 55 in a position whereby switch 75 will be moved to a circuit breaking position at the time carriage 38 moves to its rearmost position. The circuit breaking arm 80 being mounted on cam shaft 55 will rotate a slight distance beyond switch arm 76 before motor 35 and cam shaft 55 completely stops so that switch 75 will after breaking the circuit to the magnetic switch 63 return to its normally closed position.

In the use and operation of this device, when the ejector comprising the rods 46 and the lower

5 ejector member 71 move upwardly to eject the block 44, and the pallet 43, switch 68 will be momentarily closed, thereby energizing magnetic switch 63 to close the electric circuit to the motor 35. Inasmuch as switch 75 is at this time in closed position magnetic switch 63 will remain in closed position so that motor 35 will operate through one complete cycle. Carriage 38 will move forwardly to block receiving position, engaging beneath the pallet 43 and when ejector rods 46 are lowered the block 44 with the pallet 43 will rest on the arms 42 of the carriage.

10 Carriage 38 will move rearwardly and at the same time the conveyor chains 15 and 16 will move rearwardly at a relatively slow rate sufficient to move the foremost previously delivered block rearwardly a distance to permit the block now on the carriage to be delivered to the conveyor chains at the forward end of the latter. 15 As the carriage 38 moves rearwardly cam shaft 55 will rotate cam 54 to raise plate 58 so that roller 56 carried by the lifting member 52 will ride upwardly and thereby raise the block above the conveyor chains 15 and 16. The timing of the 20 cam shaft 55 is such that this shaft will make one complete revolution for each cycle of movement of the carriage 38.

25 When the carriage 38 arrives at substantially its rearmost position, arm 80 will engage switch arm 76 of switch 75, moving switch arm 76 to circuit breaking position, thereby breaking the circuit to the magnetic switch 63 and stopping motor 35. Arm 80 will override switch arm 76 a slight distance as shown in Figure 7, due to the momentum of the operating parts so that switch 75 after being moved to circuit breaking position will return to its normally closed position in order that magnetic switch 63 may be closed when a new block has been formed and is being ejected from the molding machine by the ejector plate 71. After a number of blocks 44 have been deposited on the conveyor chains 15, 16, these blocks may be lifted therefrom by a suitable lifting means for placing the blocks in a curing or setting position.

30 I do not mean to confine myself to the exact details of construction herein disclosed but claim all variations falling within the purview of the appended claims.

35 50 What I claim is:

1. A means for removing concrete blocks from a block forming means having a block ejector comprising a stationary frame, a conveyor carried by said frame, a reciprocal carriage carried by said frame including a pair of arms engageable beneath the pallet when the latter is raised by said ejector and normally disposed below the top run of said conveyor, means for reciprocating said carriage in timed relation with respect to said ejector, and means on said frame engageable with said carriage during a portion of the reciprocation thereof for raising said arms to the level of said top run for depositing the pallet on said run and then releasing the pallet.

2. A means for removing concrete blocks from a block forming means having a block ejector comprising a stationary frame, a pair of conveyor chains movably carried by said frame having one run thereof movable horizontally over the top of said frame, a carriage slidably carried by said frame and disposed between said chains, the upper edge of said carriage being disposed below the tops of said chains, means for reciprocating said carriage, a block lifting plate pivotally carried by said frame, roller means on said car-

riage engageable with said plate when the latter is raised, and means for raising said plate on the inward movement of said carriage and subsequently lowering said plate to thereby deposit a block onto said chains, and means for operating said conveyor chains.

3. A means for removing concrete blocks from a block forming means having a block ejector, comprising a stationary frame, an endless conveyor carried by said frame having a horizontal upper run, a reciprocal carriage slidably carried by said carriage, means for reciprocating said carriage, means for moving said conveyor, a pair of forwardly projecting block carrying arms carried by said carriage and adapted upon forward movement of said carriage to engage beneath the block when the latter is in ejected position with respect to the mold of said forming means, said arms being normally disposed below said upper run, and means operative upon rearward movement of said carriage for disposing said block

on said conveyor, said latter means including a plate pivotally mounted on said frame, a rotatable cam member on said frame engaging under said plate for raising the latter, roller means on said carriage engageable with said plate in the raised position thereof, and driving means operatively connected to said cam member and said carriage adapted to dispose said cam member in plate raising position when said carriage approaches the end of its rearward movement.
